FOREIGN PATENT DOCUMENTS

EP 1002477 A1 5/2000

Primary Examiner — Susan Moon Lee(74) *Attorney, Agent, or Firm* — Eckert Seamans Cherin & Mellott, LLC; David C. Jenkins(57) **CLAIM**

The ornamental design for a treatment applicator, as shown and described.

DESCRIPTION

FIG. 1 is an isometric view of the treatment applicator; FIG. 2 is a top view of the treatment applicator; FIG. 3 is a bottom view of the treatment applicator; FIG. 4 is a left view of the treatment applicator; FIG. 5 is a right view of the treatment applicator; FIG. 6 is a back view of the treatment applicator; FIG. 7 is a front view of the treatment applicator; and, FIG. 8 is another isometric view of the treatment applicator.

1 Claim, 7 Drawing Sheets(56)
